UNITED STATES PATENT OFFICE.

EDMUND CURRAN, OF BOSTON, MASSACHUSETTS.

AUTOMATIC DRILL AND WIRE GAUGE.

Application filed April 8, 1920. Serial No. 372,311.

To all whom it may concern:

Be it known that I, EDMUND CURRAN, a citizen of the United States, and resident of Boston, in the county of Suffolk and State 5 of Massachusetts, have invented an Improvement in Automatic Drill and Wire Gauges, of which the following description, in connection with the accompanying drawings, is a specification, like letters on the drawings 10 representing like parts.

My present invention is an improved, novel and automatic gauge for use in measuring the diameter of drills, wires, or other devices. Important objects of the invention 15 are to provide an efficient, accurate and quick-acting measuring device and indicating devices, showing the measurements secured, and to have these instrumentalities act automatically. Further objects of the 20 invention are to provide a strong, simple, compact construction capable of ready and instant use, with a large range of capacity for measurements, with a plurality of gauge measurements where desired, with yielding 25 means which will quickly and firmly secure the contact of the measuring devices onto the work, and hold the same with the indicator registering the corresponding measurements, as long as desired, together with 30 means to readily operate the apparatus, to automatically reset the same at zero, and to provide means for adjustment of the indicator and gauge relatively with the work 35 contacting member, for facility in assembling, to compensate for wear and the like.

Other advantages, important features and novel combinations of parts will be herein-after more fully pointed out and claimed.

Referring to the drawings, illustrating a 40 preferred embodiment of my invention,

Fig. 1 is a plan view of the indicator;

Fig. 2 is a cross-sectional view on the line 2-2 of Fig. 1;

Fig. 3 is a cross-sectional view on the line 45 3-3 of Fig. 1; and

Fig. 4 is a cross-sectional view on the line 4-4 of Fig. 3.

Referring to the drawings, 1 indicates a 50 base formed cup-shaped, adapted to receive certain of the operating devices and closed by a cover 2. The walls of the base 1 are grooved at diametrically opposite points 3 and 4, to receive a slide 5, preferably formed as a channel member with its outside walls 55 engaging the grooves 3 and 4 and the inner

or channel like portion sliding upon a rod 6, which latter is rigidly secured to the top or cover 2 by bolts 7, 7. This slide 5 extends outwardly beyond the lowermost limit of the central rod 6, the latter constituting one of 60 the work engaging devices, said slide 5 terminating in an upwardly extending lug or portion 10 carried on the lowermost part and bored to receive a short rod 12 adapted to be adjustably secured therein by a thumb-screw 120 and constituting the opposed work engaging device being adapted to cooperate with and in alinement with the fixed rod 6, the work engaging face 14 of said fixed rod 6 and the work engaging face 15 of the rod 70 12 on the slide 5, being the devices to measure the diameter of a drill, wire or the like 20, as shown in Figs. 1 and 2. The slide 5 being movable relatively with the fixed rod 6 allows for a substantial opening between 75 the faces 14 and 15, and the work contacting rods 6 and 12 being positioned centrally with regard to the slide 5, still further insure accurate measurement. As a positive 80 guiding means, also, I prefer to form on the slide 5 as indicated at 16, a collar or band enveloping the end portion of the fixed rod 6, thus still further insuring accurate alinement of the slide 5 and the registering of 85 the two work contacting faces 14 and 15. I 90 also prefer to form a groove in the cover 2, shown in dotted lines at 21, Fig. 2, and more clearly illustrated in Fig. 3 in which the upper part of the sides of the slide 5 fit, and slide therein, this constituting a guideway 95 for the slide, in addition to the recesses 3 and 4, and the collar 16. Perfect alinement is thus secured. The operation of these portions of the apparatus will be readily understood. Depressing the slide 5 separates the work contacting faces 14 and 15, and the 100 wire, drill or other article, 20, to be measured, is fitted therein, and the slide moved backwardly to contact therewith, thus measuring the desired diameter. A suitable indicator is attached and operated by this movement, as will be explained.

The measuring device just described, may be actuated by hand, but I prefer to have this operation automatic, and for this purpose I provide a spring 30 with one end attached at 31 to the base 1 or to a pin secured thereon and with the other end of said spring secured to a pin 32 fitted to the lower part 105 of the slide 5, this spring normally acting to 110

hold the slide 5 and the rod 12 upwardly so that the faces 15 and 14 will be in contact at all times. Thus a movement of the slide 5 to separate the faces 14 and 15, will be against the tension of the spring 30, and upon release of the pressure separating the working faces, and fitting the article 20 to be measured therein, the slide will automatically be returned and contact with the article 20.

I prefer to have the slide 5 firmly and yet yieldingly held into contact with the grooved part of the top 2 and for this purpose provide springs 33 and 34 guided around posts 35 and 36 respectively, which posts are secured to the base 1, and extend toward the lower part of the slide 5, said springs thus exerting a yielding tension to hold the slide 5 against the groove 21 in the plate 2 at all times, furthermore preventing rattling and insuring accurate reciprocation and measurement.

To indicate the measurement secured by the relative movement of the fixed rod 6 and slide 5, I provide a plate or cover 40, mounted, preferably, with capacity for adjustment on the topmost face of the cover 2, and fit an indicator hand 50 for relative rotation around the plate 40, said plate having thereon a plurality of graduations or gauge indications as illustrated in Fig. 1. To actuate this indicator in cooperation with the movement of the slide 5, and with the registrations of diameter of the work 20 between the faces 14 and 15, I secure to the slide 5, a rack bar 51 having teeth 52 adapted to mesh with a pinion 53 mounted on a spindle 54, having its ends bearing between the top plate 2 and the base 1, see Fig. 3. On the spindle 54 also is a gear wheel 55 which in turn meshes with a pinion 56 on a central spindle 57, having its lowermost end reduced and in a bearing in a central boss 58 formed in the base 1. This spindle 57 extends upwardly and through a flanged bushing 60, in the plate 2, to which the hub 61 of the indicator hand 50 is attached by a screw 62. This construction rotates the shaft 55 through the gears and pinions just described and in turn actuates the indicator hand 50 during the reciprocation of the slide 5. I prefer also to supply a spring 70 here shown as a coil spring fitted between plates 71 and 72, and secured to the spindle 57 with its outer end rigidly secured, whereby the indicator shaft 55 and indicator hand 50 will be independently returned to zero after the release of the work 20 between the engaging faces 14 and 15, this spring thus acting in cooperation with the spring 30, for insuring a quick return and accurate resetting of the indicator 50 to zero.

In order to provide adjustment of the dial plate 40, with the top 2, and to facilitate assembling, adjustment for wear, etc., I attach

the plate 40 by screws 41, 41, to a friction ring 42, the screws 41 extending through elongated slots 43, 43, in the top 2. This ring 42 is preferably fitted in a corresponding groove 44 in the underside of the top 2, and is sufficiently friction tight to hold the plate 40 wherever adjusted. Thus in assembling the dial plate 40 and the apparatus, and with the rod 12 in its fixed position, the plate can be readily moved radially until the indicator 50 registers at zero. Or, the adjustment to zero may be secured through the movement of the rod 12 in the lower part of the slide 5. The entire operation of the gauge and its automatic features will now be readily understood. With the dial assembled and marked with the desired graduations and adjusted with the arm 50 normally at zero, the operator depresses the slide 5, puts the drill, wire or other article to be measured, indicated at 20, between the contacting faces 14 and 15 and releases the instrument. This is all that the operator is required to do. The slide 5 instantly is retracted until the contacting faces strike the work and the indicating hand 50 is correspondingly actuated around the dial gauge.

A further important feature and advantage of the present apparatus consists in the possibility of combining both a table and the gauge indications in the single dial. Heretofore it has been customary to measure the size of drills, wire, etc., by means of one device, and then compare these measurements with a separately printed table, to determine the corresponding size of taps when it is desirable to use the same. In my present apparatus I conveniently combine both these measurements and afford an instantaneous comparison therefor. Thus for example a 20 gauge drill, as shown on the drawings, will be suitable to be used in drilling a hole for a $\frac{1}{2}$ tap; a 33 gauge for a $\frac{3}{16}$ tap, etc., as indicated around the dial surface and shown in Fig. 1. I believe that this feature is novel and important and I therefore wish to claim the same. I am also advised that it is broadly new to provide an automatic drill measuring and indicating apparatus which will effect the measurement on the drill or wire, indicate the gauge thereof, and hold said indicator in position as long as desired for the operator to note the measurements made. The automatic resetting of the dial upon removal of the wire or drill, is also believed to be new and I wish to claim this feature broadly.

My invention is further described and claimed in the form of claims as follows:

1. Apparatus of the kind described, comprising a base, a removable cover for said base, a dial on said cover there being a slide-way diametrically across the lower surface of the cover, a fixed measuring member secured to said cover, a slidable member in

the slideway enclosing the fixed measuring member and carrying a cooperating adjustable member adapted to cooperate with said fixed member to receive articles between 5 their contacting faces, a rotatable shaft, an indicator carried by the shaft, and means connecting the slidable member with said shaft, whereby the indicator is rotated a distance proportionate to the measurement of work 10 between the fixed and movable work engaging members, said indicator being movable over the dial, means securing the dial to the top side of the cover, and means permitting a rotative setting of the dial relatively with 15 the indicator, to adjust the same to zero and compensate for wear.

2. Apparatus of the kind described, comprising a base, a removable cover for said base, a dial mounted on said base there being 20 a slideway diametrically across the lower surface of the cover, a fixed measuring member secured to said cover, a slidable member movable in the slideway and car-

rying a cooperating adjustable member adapted to cooperate with said fixed member 25 and receive articles between their contacting faces, a rotatable shaft, an indicator hand carried by the shaft movable over said dial, means connecting the slidable member with said shaft, whereby the indicator hand 30 is rotated a distance proportionate to the measurement of work between the fixed and movable work engaging members, a spring to actuate the slide whereby it is normally in contact with the fixed member, means to 35 permit manual movement of the slide against the tension of the spring, to separate the fixed and movable work engaging faces, to receive work, and yielding means in the base bearing against the movable member to hold 40 it firmly in engagement with the guideway in the cover.

In testimony whereof, I have signed my name to this specification.

EDMUND CURRAN.
